UNITED STATES PATENT OFFICE.

WILLIAM A. BOYDEN, OF HARRISBURG, PENNSYLVANIA, ASSIGNOR TO
WILLIAM E. DOUGHERTY, OF SAME PLACE.

IMPROVEMENT IN CAR-COUPPLINGS.

Specification forming part of Letters Patent No. **159,636**, dated February 9, 1875; application filed
August 5, 1874.

To all whom it may concern:

Be it known that I, WILLIAM A. BOYDEN, of Harrisburg, in the county of Dauphin and State of Pennsylvania, have invented an Improvement in Automatic Car-Couplers, of which the following is a specification:

My invention relates to the combination of an angle-iron with the interior of the inner end of the draw-head, the said angle-iron being confined thereto by means of a pin, and against the follower by means of the head of the spring-bolt, as hereinafter fully described.

In the accompanying drawings, Figure 1 is a plan view of the contiguous platforms of two cars, the upper and front portions of one platform being removed to show the arrangement of my improvements with the draw-head more clearly. Fig. 2, Sheet No. 2, is a side elevation of one of the platforms and parts attached, and a vertical section at the line *x x* of Fig. 1.

Like letters of reference in both figures indicate the same parts.

A A are the platforms of the contiguous ends of two cars with my improved coupler in connection therewith. B B are the draw-heads. They have division-plates *a* in their front ends, of different heights, for holding the coupling-link C in accommodation to cars of different heights. D D are the followers of the coupling-link. They have horizontal grooves *b*. In the inner ends of the draw-heads B are angle-irons E, which are secured by means of pins F. (Shown clearly in the vertical section

of Fig. 2.) The angle-irons E and followers D are held firmly together between the front ends of the springs H and the head of the rods I, to give a strong support to the draw-heads when the followers are brought to rest. The coupling-pins J are elevated by means of the rocking shafts K, provided with lifting-arms L, in combination with the connecting-rods M and lifting-bar L'. (Shown clearly in Fig. 2.) The rocking shafts are so arranged as to their vertical position as to cause the lifting-arms to rest upon the platforms A as a support when the pins J are in their lower position, and to facilitate the free vertical movement of said pins. The levers N on the ends of the rocking shafts are so arranged as to turn the rocking shafts K in such a manner as to cause the descent of the coupling-pins J when two contiguous cars are brought together, and the coupling-links C have forced the followers D backward far enough to admit of the descent of the pins J, the lower ends of which previously rest upon the upper edges of the followers.

Hand-wheels provided with counter-weights may be used instead of the levers N.

I claim as my invention—

The combination of the angle-iron E, pin F, draw-head B, follower D, and the spring-rod I, for holding the draw-head in its forward position, substantially as described.

WM. A. BOYDEN.
